UNITED STATES PATENT OFFICE.

HERRMANN LIETZ, OF PITTSBURG, PENNSYLVANIA.

TROLLEY.

No. 923,540.

Specification of Letters Patent.

Patented June 1, 1909.

Application filed January 9, 1909. Serial No. 471,507.

To all whom it may concern:

Be it known that I, HERRMANN LIETZ, a citizen of the United States of America, residing at Pittsburg, in the county of Allegheny and 5 State of Pennsylvania, have invented certain new and useful Improvements in Trolleys, of which the following is a specification, reference being had therein to the accompanying drawing.

10 This invention relates to trolleys, and the object of my invention is to provide a novel device to assist the replacing of a trolley wheel upon a trolley wire, should the same be accidentally displaced due to irregularities 15 in the wire, rapidity of operation or curves in a railway system.

My trolley replacing device is constructed to normally retain a trolley wheel upon a trolley wire, which is made whereby the device 20 can recede when encountering trolley hangers and all overhead work of a railway system.

The detail construction entering into my invention will be hereinafter described and 25 then specifically claimed.

Referring to the drawings:—Figure 1 is a side elevation of a trolley device, and Fig. 2 is a front elevation of the same.

In the accompanying drawings, 1 designates 30 a trolley pole having a harp 2, between the arms 3 of which is journaled a trolley wheel 4; said wheel being adapted to travel upon a wire 5. The arms 3 extend above the periphery of the trolley wheel 4 and are 35 beveled inwardly, as at 6.

The sides of the harp 2 are provided with depending parallel anchor-shaped plates 7, the anchor ends of which are connected, as at 8, and provided with apertured lugs or eyelets 9. Pivotaly connected to the harp 2 by a bolt 10 and a nut 11 are replacer arms 12, said arms extending upwardly above the harp arms 3 and flared outwardly, as at 13, at an angle corresponding to the bevel of the 45 upper ends of the harp arms 3. The lower ends of the replacer arms 12 are provided with eyelets 14 and these eyelets are connected by coil springs 15 to the apertured lugs or eyelets 9. The tension of the springs 50 15 is adapted to normally maintain the replacer arms 12 parallel with the arms 3 of the harp 2 and when a cross wire, trolley hanger or similar overhead construction is encountered, the upper ends of the arms 12 can recede to pass such structure, and then the 55

springs 15 will return said replacer arms to their normal position. The lower inner edges of the replacer arms 12 are provided with inwardly projecting guides 16 extending upwardly inside of the anchor-shaped plates 7, to prevent the arms 12 from wabbling.

My trolley replacer is made of metal and is applicable to the present type of trolley harp.

While in the drawings forming a part of this application there is illustrated the preferred embodiments of my invention, I would have it understood that the same can be varied or changed as to shape, proportion and manner of assemblage without departing from the spirit of the invention.

Having now described my invention what I claim as new, is:—

1. The combination with a trolley pole, a harp carried thereby and having a wheel journaled between the arms of said harp, of anchor-shaped plates fixed to the outer sides of said harp, apertured lugs carried by the anchor ends of said plates, replacer arms pivotally supported by the sides of said harp and having the upper ends thereof flared outwardly above the periphery of said trolley wheel, eyelets carried by the lower ends of said replacer arms, springs connecting said eyelets to the pierced lugs of said anchor plates, and inwardly extending guides carried by the lower edges of said replacer arms and extending upwardly at the inner sides of said anchor plates for guiding the movement of said replacer arms, substantially as described.

2. The combination with a trolley harp, a trolley wheel journaled between said harp, of anchor plates secured to the sides of said harp, replacer arms pivotally carried by the sides of said harp and having the upper ends thereof extending above the periphery of said wheel, guides carried by the inner lower edges of said replacer arms and adapted to embrace the lower edges of said anchor plates, and means connecting the lower ends of said replacer arms and the anchor ends of said plates for connecting said replacer arms parallel with said harp.

In testimony whereof I affix my signature in the presence of two witnesses.

HERRMANN LIETZ
